(57) CLAIM

I claim the ornamental design for shorts, as shown and described.

DESCRIPTION

FIG. 1 is a perspective view of shorts, showing my new design;

FIG. 2 is a perspective view thereof, illustrated with the inner portion thereof inverted and inside-out with respect to the outer portion thereof;

FIG. 3 is a front elevational view of FIG. 1;

FIG. 4 is a rear elevational view of FIG. 1;

FIG. 5 is a right-side elevational view of FIG. 1, the left-side elevational view being a mirror image thereof;

FIG. 6 is a top plan view of FIG. 1; and,

FIG. 7 is a bottom plan view of FIG. 1.
